UNITED STATES PATENT OFFICE.

CHARLES J. FANCHER, OF WINDSOR, VERMONT, AND ROBERT A. JOHNSON, OF LONG-MEADOW, MASSACHUSETTS, ASSIGNEES, BY MESNE ASSIGNMENTS, TO WOODWARD-HUBBARD COMPANY, OF HILL, NEW HAMPSHIRE, A CORPORATION OF NEW HAMPSHIRE.

STRIP-FEEDING MECHANISM.

Original application filed January 12, 1927, Serial No. 160,639. Divided and this application filed December 21, 1927. Serial No. 241,573.

Our invention relates to improvements in mechanism for feeding strips, and particularly for feeding strips of zinc while being cut into glaziers' points, the same being a 5 divisional part of our application for Letters Patent of the United States, filed January 12, 1927, Serial No. 160,639.

The primary object of our invention is to produce mechanism with which can be fed 10 to cutting mechanism one or more strips of zinc, or more or less similar material, in a manner to insure precision, adequacy, and reliability, said feeding mechanism being comparatively simple both structurally and 15 functionally.

Another object is to provide mechanism of this character with means for feeding the strips at their leading ends intermittently, even though said strips initially be fed 20 continuously. For this purpose clamping and slip-feeding elements are employed and applied to the strips.

In order to feed zinc strips to the best advantage to cutting mechanism, feeding 25 mechanism is required which is especially adapted for handling such strips. The feeding of zinc strips, as distinguished from the feeding of spring-steel strips for example, involves the use of means especially 30 adapted for the purpose, and necessarily different from means capable of feeding strips of material of a character unlike zinc, or having characteristics which differ from those of zinc, as will be readily understood.

Our feeding mechanism is designed to handle and feed ten zinc strips, but this number as applied to said mechanism may be increased or decreased without changing any 40 essential feature of the mechanism or departing from the invention, since even a single strip might be fed thereby without making any mechanical change, or mechanism might be constructed to handle a single strip 45 only, or to handle more than ten strips. In this connection it may be noted that, when the feeding mechanism is employed in connection with the manufacture of glaziers' points, the strips are obtained from a roll 50 of sheet zinc sufficiently wide to cut therefrom the required number, as ten, of said strips each equal to the width of a diamond-

shaped point between parallel sides. The stock, after being cut in a slitting machine into the ten, more or less, individual strips, 55 is rolled on large spools which are supplied as required to the feeding mechanism.

Other objects and advantages will appear in the course of the following description.

A preferred embodiment of the invention, 60 whereby we attain the objects and secure the advantages of the same, is illustrated in the accompanying drawings, and we will proceed to describe the invention with reference to said drawings, although it is to be 65 understood that the form, construction, arrangement, etc., of the parts in various aspects are not material and may be modified without departing from the spirit of the invention.

In the drawings, in which like reference characters designate like parts throughout the several views, Figure 1 is a front elevation of feeding mechanism which embodies a practical form of our invention as aforesaid; Fig. 2, a top plan of certain parts and members of the feeding mechanism which may be and here are in the form of an attachment mounted on the cutter-head, and which may be removed therefrom; Fig. 3, 70 a rear elevation, broken away on different longitudinal, vertical planes, of parts of said attachment; Fig. 4, a cross section through the parts and members appearing in Fig. 3; Fig. 5, a front side elevation of said attachment; Fig. 6, a front end elevation of said attachment; Fig. 7, a top plan of 75 said cutter-head, which is so closely associated with said feeding mechanism as to form a part thereof; Fig. 8, a front side elevation of said cutter-head; each of Figs. 9, 10, 11, and 12, a sectional detail illustrating a stage of the feeding operation; Fig. 13, a transverse, vertical section through said cutter-head, and, Fig. 14, a longitudinal, vertical section through the cutter-head.

We have illustrated our feeding mechanism with or as a part of a glazier's-point machine, and will describe so much of said machine as is shown or may be necessary fully to understand said mechanism in both structure and function. It is to be understood, of course, that the strip-feeding mech-

anism can be applied to or used in connection with a machine or machines other than a glazier's-point machine.

A bed block 1 is supported on a table 2, 5 a portion of said block inclining downwardly from rear to front to provide a bed 3 for a cutter-head bed 4. The bed 4 has at the right-hand end bearings 5—5 for a transversely arranged, oblique shaft 6. Posts 7, 10 each having its base firmly set in the bed block 1, are rigidly connected at the top by means of a platform 8. Secured on the platform 8 is a plate 9 above which is journaled in suitable bearings a horizontal shaft 10. A feed wheel 11 is mounted on and secured to the forward end of the shaft 10. A stand 12 rises from the plate 9 and has at the upper end a bearing for a short horizontal shaft 13, on which is mounted a 15 weighted arm 14. The arm 14 carries a roll 15 and locates the same directly over the top of the wheel 11. The wheel 11 is continuously driven by any suitable means and from any suitable source of power, as is also 20 the shaft 6. Here the shaft 6 is provided with a cone 16 as the direct driving member.

Ten zinc strips 17, from a spool (not shown), are passed upwardly through a slotted guide bar 18, over the wheel 11 and between said wheel and the roll 15, into and 30 through a holder 19, and into ten tubes 20. The bar 18 is supported by an arm 21 that is rigidly attached to one of the posts 7. The tubes 20 are arranged side by side, being 35 held together by means of links 22—22, and are supported at their upper ends by the holder 19, and at their lower ends by an arm 23 that is also rigidly attached to one of the posts 7. The tubes 20 extend to the 40 left from the holder 19, then curve downwardly and to the right, and finally descend to a plane at some distance above the cutter-head.

Inasmuch as the strips 17 are fed vertically to the cutter-head, and it is essential, 45 after the first cut is made, to produce a plurality of glaziers' points at each active stroke of the movable cutter, it is necessary that said cutter-head be set obliquely to the vertical plane of the strips where they are fed to the cutters. Furthermore, as it is preferred that each point be equal in width, between either pair of its oppositely disposed edges, to the width of the strip from 50 which the point is cut, the cutter-head is set at an angle of 40° to the vertical plane of said strip, that being the degree angle of two parallel edges of said point when the latter is placed vertically on one of said edges. 55 Due to this angular setting or position of the cutter-head, the same is shown in Fig. 1 as it is actually located in and as a part of the machine, wherein said cutter-head inclines downwardly and forwardly from the back to the front side of said machine.

The sides of the cutter-head bed 4 are at right-angles to the top and bottom thereof. This bed carries cutting mechanism that includes a fixed knife 24. Plates 25 and 26, which form parts of the feeding attachment, 60 are arranged to reciprocate above the knife 24, as will presently appear. There are ten vertical grooves 27 in the side of the plate 26 which is contiguous with the plate 25, and the strips 17, after they leave the bottom 65 ends of the tubes 20, which ends are directly above said plates and said grooves, pass down between said plates and through said grooves, and emerge at the right-hand side of the knife 24, the inner side of said plate 25 so being in the same plane with said side of said knife. The plate 26 has a base piece 28 which extends under the plate 25 and is directly over the knife 24. The plate 25 is secured by means of screws or otherwise 70 to the plate 26. On the front side of the plate 25 are two sleeves 29 which are adapted to slide on two guide rods 30.

A fixture 31 is secured by means of bolts 32—32 respectively to a lug 33, on the back 75 side of the bed 4, which is tapped at 34 to receive one of said bolts, and to the top of said bed adjacent to the front side thereof which has another tapped opening 34 therein to receive the other of said bolts. Another fixture 35 is secured by means of two bolts 36 to the front side of the bed 4, tapped openings 37, Fig. 3, being provided in said side 80 to receive said bolts. A stud 38 is tapped into an opening 39 also in the front side of 85 the bed 4. The fixture 31 is crosswise of the bed 4, and therefore inclined at an angle of 40°. The fixture 35 has a sleeve 40 in which 90 is adapted to slide up and down a rod 41 parallel with the front side of the bed 4, and the stud 38 extends forwardly and downwardly from said side. Mounted on and secured to the front end of the shaft 6 is a 95 cam 42.

The fixture 31 has two lugs 43 on top, and 100 the guide rods 30 have their bases firmly set in said lugs, and extend vertically upward therefrom. A plate 44 extends between the sleeves 29 and forms with them a feeding-head for and at the right of the plates 25 105 and 26. The plate 44 has a row of openings therethrough, from front to back and adjacent to the top thereof, to receive loosely therein ten horizontal tension pins 45, and has the same number of pivot pins 46 set in 110 the back side thereof directly below said first-named pins. Each pin 45 is in the form of a screw, and has its rear terminal tapped into a presser finger 47. These ten fingers 115 mounted on the pivot pins 46, and have at the bottom ends rearwardly extending parts 48 that enter slots 49 in the plate 26 to press against the strips 17 at the left of said parts. The fingers 47 depend from the pins 45, and 120 the angular bases of said fingers are per- 125

mitted to press against the strips 17 in the grooves 27, because the slots 49 open into said grooves at the right of the base 28—see Fig. 12. A spring 50 is interposed between 5 a washer 51, which is on each pin 45 and bears against the head thereof, and the adjacent side of the plate 44, whereby the finger 47 with which said pen is engaged is yieldingly held with its lower terminal in 10 advanced position and its projection 48 pressed against the strip 17 at the left of said projection. The amount of tension of any spring 50 can be varied by turning the associated pin 45 in or out of the finger 47 15 with which said pin is engaged.

It is now evident that the feeding-head with its fingers 47 and the plates 25 and 26 constitutes a feeding unit that can be moved up or down on the guide rods 30. Although 20 the presser fingers 47 at their lower ends constantly engage frictionally the strips 17, this engagement is of such a nature that the whole unit moves upwardly without difficulty, when said strips are held stationary 25 from below, as they are intermittently by parts of the cutter-head yet to be described, and that said strips are carried downwardly with said unit when the same descends.

The required reciprocating movement is 30 imparted to the aforesaid unit by means of the cam 42, a lever 52, links 53 and 54, a lever 55, and a link 56. The lever 52 is mounted to rock on the stud 38, and said lever at its right-hand end is equipped with 35 a roll 57 which is received in a cam-groove 58 in the cam 42. The upper end of the link 53 is pivotally connected at 58 with the left-hand end of the lever 52, and the lower end of said link is pivotally connected at 59 with 40 a block 60. The lower end of the link 54 is pivotally connected at 61 with the block 60, and the upper end of said link is pivotally connected at 62 with the forward end of the lever 55. The lever 55 is mounted to rock 45 on a stud 64 projecting from the right-hand side of the fixture 31 near the front end thereof. The lower end of the link 56 is pivotally connected at 65 with the rear end of the lever 55, and the upper end of said link 50 is pivotally connected at 56' with the plate 44 in the center and near the bottom edge thereof, said link being at the right of said plate.

As the cam 42 rotates, it oscillates the lever 52, through the medium of the roll 57, said lever causes the lever 55 to be oscillated through the medium of the links 53 and 54 and their pivotal connections, and said last-named lever, through the medium of the link 56, imparts a reciprocating movement to the feeding-head and all the parts and members carried thereby. At each revolution 60 of the cam 42, the presser fingers 47 move up with the plates 25 and 26 on the strips 17, and with said plates move down

again carrying with them said strips. The cutting mechanism and the cam 42 are so relatively timed that the strips 17 are held securely while the fingers 47 ascend, and so prevent said fingers from carrying with them 70 said strips, but are released when the fingers descend, so that the latter carry down with them the strips into position to have a row of points cut therefrom. The base 28 of the plate 26 descends nearly to the top of the 75 knife 24.

If it be desired to remove the attachment for any reason, the bolts 32 are taken out, the lever 52 is detached from the stud 38, the levers and links below the fixture 31 are 80 disconnected, and said fixture and the parts and members supported thereon and thereby are removed from the bed 4. The bolts 36 are taken out and the fixture 35 is removed from the bed 4, and the stud 38 is unscrewed 85 from said bed.

Arranged to slide longitudinally on the bed 4 is a carriage 66, which carriage has a depending lug 67. Another carriage 68 is mounted on the carriage 66 for longitudinal 90 movement. A horizontal rod 69 is arranged in the lug 67 and a cross-piece 70 of the bed 4, with a spring 71 interposed between said cross-piece and said lug. Threaded onto the right-hand end of the rod 69, at the right of the lug 67, is a nut 72. The spring 71 forces the lug 67 against the nut 72, and exerts a constant pressure to the right on said lug and the carriage 66. Slidingly arranged in the longitudinal center of the carriage 66 is 95 a rod 73. This rod projects beyond the right-hand end of the carriage 66, and is forced to the right by means of a spring 74 interposed in said carriage between the left-hand end of said rod and a plug 75 tapped into 100 the corresponding end of the passage provided in said carriage for said rod, spring, and plug. There is a vertical opening 76 in the carriage 66, and a pin 77 extends downwardly from the carriage 68 into said opening, said pin being rigidly attached to the rod 73. The opening 76 is larger than the pin 77 to allow said pin to move back and forth therein, and the spring 74 tends constantly to force the rod 73, said pin, and the 105 carriage 68, to the right. The top of the carriage 68 at the right-hand end is elevated, and secured to the elevated portion are ten 110 holding rods 78. These rods are arranged side by side and extend to the left over the top of the carriage and through a block 79 secured to said carriage at the left-hand end thereof, and through a movable knife 80 let into and rigidly secured to said block at said end. Bolted to the right-hand end of a bed 115 block 81 secured to the top of the bed 4, at the left of the block 79, is a gage-bar 82 which receives the descending strips 17 and assists in positioning them for cutting.

The fixed knife 24 is mounted on the bed 130

block 81 and secured thereon by means of an angular bar 83 bolted to the top of the bed 4, together with bolts with which said bar is equipped. The base 28 of the reciprocating plate 26 plays up and down in front of that part of the bar 83 that is on the knife 24. In the block 81, beneath the knife 24, are ten channels 84 to receive the points as they are cut from the strips, and wherein said points 10 are held intermittently by the rods 78.

Mounted on and bolted at 85 to the block 79 and extending to the left over a portion of the movable knife 80 is a guide bar 86, and having its ends rigidly secured to said bar is a U-shaped guide bar 87. Slidably arranged in the bars 86 and 87 are ten clamping plungers 88, each provided intermediate of its ends with a collar 89. The passages in the bar 86 for the plungers 88 are enlarged 20 at their right-hand terminals to accommodate the collars 89. Interposed between the transverse part of the bar 87 and the collars 89 are springs 90. These springs have a constant tendency to force the collars 89 and the 25 plungers 88 to the left or toward the fixed knife.

The knife 80 is adapted, when actuated to the left or advanced, to make with the bottom right-hand edge of the knife 24 30 shearing cuts on the vertical strips 17, which cuts are at an angle of 40° to the strips. The rods 78 are in line with the channels 84, and the plungers 88 are at the right of the right-hand side of the 35 knife 24.

A transverse rock-shaft 91 is journaled in the bed 4 below and a little to the left of the shaft 6, and mounted on and secured to said rock-shaft are upwardly extending 40 arms 92 and 93, the former being shorter than and in front of the latter. The arm 92 bears at its upper terminal against the outer end of the rod 73. A roll 94 is mounted on a transverse shaft 95 journaled 45 in two bearings 96 that rise from the carriage 66 at the right-hand end thereof. Mounted on and secured to the shaft 6 between the bearings 96 are two cams 97 and 98, the former being larger than and in 50 front of the latter. The cam 97 is in contact with the roll 94, which roll is at the left of said cam, and the cam 98 is in contact with the arm 93, which is also at the left of its cam.

55 At each revolution of the shaft 6, the cam 97, acting on the roll 94 and through the medium of the shaft 95 and the bearings 96, forces the carriage 66 to the left, or advances it, against the resiliency of the spring 60 71, and permits said carriage to be returned by said spring to retracted or initial position, and at the same time the cam 98 acting on the arm 93 rocks said arm to the left on the rock-shaft 91 and with it the arm 92, 65 and said last-named arm forces the rod 69

to the left, against the resiliency of the spring 71, with the result that the carriage 68 is moved to the left or advanced, through the medium of the pin 77, and then said last-named spring acts to move said last-named carriage to the right into retracted or initial position. 70

Referring to Figs. 9, 10, 11, and 12, in the order named, it will be seen that, while the movable knife 80 and the clamping 75 plungers 88 are in retracted position, and the feeding-head is descending with the strips 17, the points (represented at 99) in the channels 84 are prevented from falling out of the entrances to said channels by the holding rods 78; that, as said strips are carried down further by said feeding-head, they descend over said entrances into position to hold said points in place, said rods are withdrawn from the paths of said 85 strips, and said knife and said plungers begin to advance; that, by the time the strips are moved down by the feeding-head until their lower ends contact with the gage-bar 82, the strips are clamped by said plungers 90 against the face of the fixed knife 24, said movable knife advances into cutting position, and said rods are retracted so that they no longer project to the left beyond 95 said movable knife; and that, while the strips are clamped by the plungers, the movable knife continues to advance and cuts a set of ten points from the lower end portions of the strips which cover the entrances to said channels. Next, the movable knife 100 and clamping plungers recede, the holding rods advance, and the feeding-head rises to its highest position, the finger projections 48 then slipping on the strips, the parts and members again being disposed as in Fig. 4. 105

From the channels 84 the points 99, as they accumulate, are forced into ten channels 100 in a carrier 101 which extends to the left from the bed block 81.

Assuming that ten zinc strips 17 have had 110 their leading ends passed between the feed wheel 11 and the feed-tension roll 15, introduced into the holder 19, and moved on into and through the tubes 20, and down between the plates 25 and 26 in the grooves 27, onto the gage-bar 82, and that said feed wheel and the shaft 6 are in motion, the operation of said mechanism is described as follows: 115

At each revolution of the cams 97 and 98, on the shaft 6, the knife 80, clamping plungers 88, and holding rods 78 are operated to cut ten points from the bottoms of the strips 17, and to advance the points previously cut and in the channels 84 a distance in said channels equal to the thickness of one point. The strips 17 are fed constantly, although having their lower ends momentarily retarded by the gage-bar 82 and the clamping plungers 88 while the cut 125 is being made each time. Whatever slack 130

in the strips may occur during the time they are clamped is distributed and taken care of in the tubes.

The feeding-head which reciprocates on the rods 30 and includes the fingers 47, carries the plates 25 and 26 down and with them the strips 17 a distance equal to the width of a point 99 between any two of its parallel sides, while the plungers 88 are out of contact with said strips, and said feeding-head rises the same distance and carries with it said plates while said plungers are in clamping relationship with said strips, said plates and the finger ends 48 then sliding upwardly on the stationary strips without affecting them.

The ten points are cut from the ten strips 17 at an angle of 40° by the knives 24 and 80. These points are pushed into the channels 84 by the cutting parts of the knife 80, and held there by the rods 78 while said knife is retracted and until said strips are moved down in front of said points.

We claim:

1. In strip-feeding mechanism, clamping means for a strip, reciprocating means to feed said strip in operative relation to said clamping means, and to slip on said strip while the same is being held by said clamping means, said reciprocating means comprising members which form a straight and unbroken course for said strip, and yieldingly held fingers located adjacent to said course.

2. In strip-feeding mechanism, clamping means for a strip, rotary feeding means for said strip, and a head having guide plates which form a straight and unbroken course for the leading-end portion of said strip, and provided with yieldingly held fingers frictionally to engage said strip in said course, whereby the strip is fed in operative relation to said clamping means, and said plates and fingers slip on said strip while the same is held by said clamping means.

3. In strip-feeding mechanism, a fixture, a feeding-head mounted to reciprocate on said fixture, having attached thereto guide plates forming straight and unbroken courses for strips to be cut, and provided with yieldingly held fingers arranged frictionally to engage said strips in said courses, without bending or penetrating the strips, and operating means for said feeding head, said fingers being independent of said means.

4. In strip-feeding mechanism, holding means for strips, reciprocating guide plates forming straight and unbroken courses for said strips, and yielding means to cause said strips to move with said plates in one direction, but adapted to slip with said plates on said strips when the latter are held by said holding means and the plates are moved in the opposite direction, all without bending or penetrating said strips.

5. In strip-feeding mechanism, reciprocating

ing guide plates forming a course for strips, 70 a supporting member traveling with said plates, and spring-pressed fingers pivotally connected with said member and having parts to bear on said strips in said courses.

6. The combination, in strip-feeding 75 mechanism, with a bed, and a shaft and a cam thereon, of a fixture attachable to and detachable from said bed, a feeding-head mounted to reciprocate on said fixture, having attached thereto guide plates for strips, 80 and provided with yieldingly-held fingers arranged frictionally to engage said strips, and operating means for said feeding-head, said means being operatively connected with said cam, and pivotally connected with said 85 bed and said feeding-head, said fingers being independent of said means.

7. The combination, in strip-feeding mechanism, with a laterally inclined bed, of 90 a fixture attachable to said bed crosswise thereof, a feeding head mounted to reciprocate on said fixture, having attached thereto guide plates for strips to be cut obliquely, the bottom edges of which plates incline with the inclination of said bed, and being provided with yieldingly held vertical fingers 95 arranged frictionally to engage said strips, and operating means for said feeding-head, said fingers being independent of said means.

8. The combination, in strip-feeding 100 mechanism, with a laterally inclined bed, and a shaft and a cam thereon, of a fixture attachable to and detachable from said bed crosswise thereof, a feeding-head mounted to reciprocate on said fixture, having attached 105 thereto guide plates for strips to be cut obliquely, the bottom edges of said plates corresponding with the inclination of said bed, and said feeding-head being provided with yieldingly-held vertical fingers arranged frictionally to engage said strips, and operating means for said feeding-head, said 110 means being operatively connected with said cam, pivotally connected with said bed and said feeding-head, and independent of said 115 fingers.

9. The combination, in strip-feeding mechanism, with a bed, and a shaft and a cam thereon, of a fixture adapted to be secured to said bed, a feeding-head mounted 120 to slide on said fixture, carrying guide plates for strips, and equipped with yieldingly-held fingers arranged to bear on said strips, a lever pivotally connected with said bed and in engagement with said cam, a lever pivotally connected with said fixture and having a link connection with said sliding member, a guide member fastened to said bed, a guide rod slidably arranged in said guide member, and link connections between said rod 125 and said levers.

10. In strip-feeding mechanism, a reciprocating member, fingers pivotally connected with said member, spring-pressed pins

loosely mounted in said member and connected with said fingers, and a strip guide arranged to move with said member, the construction and arrangement of parts being such that said fingers yieldingly engage the strips in said guide.

11. In strip-feeding mechanism, a fixture provided with guide rods, a plate having sleeves mounted to slide on said rods, a plate grooved to receive said strips and a cover plate therefor, both plates being rigidly connected with said sleeves, fingers having pro-

jections and being pivotally mounted on said first-named plate between the same and said grooved plate, which latter is perforated to receive said projections, and spring-pressed pins loosely mounted in said first-named plate and connected with said fingers, the arrangement and construction of parts being such that said projections normally are adapted frictionally to engage said strips in said grooves.

CHARLES J. FANCHER,
ROBERT A. JOHNSON.
